GOLF CLUB HEAD

John Reuter, Jr., Box 8155, 615 E. Broadway,
Phoenix, Ariz.

Filed July 27, 1959, Ser. No. 56,945

Term of patent 14 years

(Cl. D34—5)

The dominant feature of my design resides in the beveled portions at the heel and toe end of the club face to provide a substantially tri-planar appearance as shown.

I claim:

The ornamental design for a golf club head, substantially as shown and described.
